UNITED STATES PATENT OFFICE

171,495

COIN OPERATED VENDING MACHINE

Walter R. Gray, Redondo Beach, Calif., assignor
to Mercury International Manufacturing Cor-
poration, a corporation of California

Application February 20, 1953, Serial No. 23,713

Term of patent 3½ years

(Cl. D52—3)

To all whom it may concern:

Be it known that I, Walter R. Gray, a citizen of the United States of America, residing at Redondo Beach, county of Los Angeles and State of California, have invented a new, original, and ornamental Design for a Coin Operated Vending Machine, of which the following is a specification, reference being had to the accompanying drawing, forming a part thereof.

Figure 1 is a perspective view showing the front and lefthand side of a coin operated vending machine, embodying my new design;

Figure 2 is a top plan view of the machine of Figure 1;

Figure 3 is a front elevation of the machine of Figure 1; and

Figure 4 is a side elevation taken from the righthand side of the machine of Figure 1.

I claim:

The ornamental design for a coin operated vending machine, substantially as shown.

WALTER R. GRAY.
